UNITED STATES PATENT OFFICE.

GUSTAVO PAOLO BREITER, OF MILAN, ITALY.

DESIGN FOR A BOTTLE FOR DUSTLIKE MATERIALS.

46,425.

Specification for Design.

Patented Sept. 22, 1914.

Application filed March 9, 1914. Serial No. 823,586. Term of patent 3½ years.

To all whom it may concern:

Be it known that I, GUSTAVO PAOLO BREITER, a subject of the King of Italy, residing at 8 Via Meravigli, Milan, Italy, have invented a new, original, and ornamental Design for a Bottle for Dustlike Materials, of which the following is a specification, reference being had to the accompanying drawing, forming a part thereof.

Figure 1 is an elevation of a bottle, showing my new design, and Fig. 2 is a top plane view thereof.

I claim:

The ornamental design for a bottle for dust-like materials as shown.

In testimony whereof I have set hereunto my hand in presence of two witnesses.

GUSTAVO PAOLO BREITER.
